[57] CLAIM

The ornamental design for a utility load body, as shown
and described.

DESCRIPTION

FIG. 1 is a perspective view of a utility load body showing
my new design;

FIG. 2 is a rear end elevational view thereof;

FIG. 3 is a side elevational view thereof; and

FIG. 4 is a bottom plan view thereof.

The broken lines illustrate the association of a towing
tongue door handles and wheels when the utility load
body is used as a trailer and are shown for illustrative
purposes only.
